United States Patent Office

Des. 180,855
Patented Aug. 20, 1957

180,855

DECANTER

Sol Young, Brooklyn, N. Y., assignor to L. Batlin & Son, Inc., New York, N. Y., a corporation of New York

Application November 13, 1956, Serial No. 43,719

Term of patent 3½ years

(Cl. D58—9)

Fig. 1 is a front view of a decanter embodying my new design;

Fig. 2 is one side view thereof;

Fig. 3 is another side view thereof; and

Fig. 4 is a rear view thereof.

I claim:

The ornamental design for a decanter, as shown.
